ATTORNEY.

UNITED STATES PATENT OFFICE.

HENRY N. WADE, OF MILWAUKEE, WISCONSIN, ASSIGNOR TO THE CUTLER-HAMMER MFG. CO., OF MILWAUKEE, WISCONSIN, A CORPORATION OF WISCONSIN.

THERMOSTATIC SWITCH.

Application filed November 24, 1919. Serial No. 340,205.

To all whom it may concern:

Be it known that I, HENRY N. WADE, a citizen of the United States, residing at Milwaukee, in the county of Milwaukee 5 and State of Wisconsin, have invented new and useful Improvements in Thermostatic Switches, of which the following is a full, clear, concise, and exact description, reference being had to the accompanying 10 drawing, forming a part of this specification.

This invention relates to thermostatic switches adapted for various uses as in heating and refrigerating systems.

15 The present forms of thermostatic switches employ solid contacts and due to the slow motion of the thermal operating means commonly employed, such contacts tend to draw destructive arcs unless additional means are provided to insure quick disengagement thereof. Also, owing to the slow closure of such switches any vibrations thereof during closure tend to cause their contacts to vibrate which often results 20 in further arcing and sometimes welding of the contacts.

The present invention has among its objects to provide a simple and reliable thermostatic switch which will overcome the 30 aforesaid and other disadvantages of the present thermostatic switches.

Another object is to provide a thermostatic switch which will minimize the work required of the thermal means.

35 Other objects and advantages of the invention will hereinafter appear.

The accompanying drawing illustrates one embodiment of the invention which will now be described, it being understood that 40 the same is susceptible of various modifications falling within the scope of the appended claims.

45 Referring to the drawing, the structure shown therein comprises a mercury switch 1 fixed to an insulating sector 2 mounted upon a knife edge pivot stud 3 projecting from a support 4 and a thermal element 5 for oscillating the sector 2.

The switch 1 comprises an insulating vessel, preferably a glass tube, containing a 50 quantity of mercury or other preferred fluid 6 and having sealed in its ends terminal wires 7 and 8 to be bridged by the mercury. The tube is provided with wells 9 and 10 for the mercury, the quantity of which is

sufficient to bridge said wells and the extremities of the terminal wires 7 and 8 are arranged to extend into said wells for constant immersion. Thus it will be apparent that tilting of the switch 1 without emptying the wells will cause the mercury to divide to break circuit between the terminals 7 and 8 and due to the surface tension of the mercury a quick break will be insured even though the switch be tilted very slowly. Similarly, return of the switch to the position illustrated will cause the main body of the mercury to recombine with the mercury in the well or wells for a quick and decisive closure of the circuit between 70 the terminal wires.

Also, the tube is preferably so formed and mounted as to render the mercury supporting surface thereof, except for the wells, concentric to the pivot of the sector 2 whereby the center of gravity of the bulk of the mercury will remain substantially fixed vertically when the switch is tilted by pivotal movement of the sector which is 75 preferably provided with a counter-balance 11. Such provisions render the switch operable by a very slight force, thus minimizing the work required of the thermal means.

The switch is provided with ferrules 12 and 13 fitted to the ends thereof and electrically connected with the terminal wires 7 and 8 respectively. The sector is provided with conducting clips 14 and 15 to receive the ferrules 12 and 13 respectively and the switch is so positioned on said sector as to complete circuit when the latter 90 bears against the stop 16 provided on the support 4. The clips 14 and 15 have conducting leads 17 and 18 respectively which are coiled about the hub of sector 2 and 95 connected to binding posts 19 and 20 respectively provided on the support 4.

The thermal element, which in practice may assume various forms is shown as comprising a bimetallic strip connected at one 100 end to a post 21 on the support 4 and having its opposite end connected to a stud 22 mounted on the sector and adjustable radially thereof. The thermal strip is utilized to rotate the sector clockwise, the adjustable stud 22 providing for variation of the 105 range of movement of said disk for a given temperature variation. With such an arrangement the mercury divides adjacent to the well 9 for interruption of circuit al- 110

- 2
- though it is to be understood that the stop 16 might be placed on the opposite side of the sector and the thermal strip employed to rotate the sector counterclockwise 5 to divide the mercury adjacent to the well 10. Thus the switch may be readily designed to open circuit either upon an increase or decrease of temperature as desired and as will be apparent the switch might 10 be normally held in a position to interrupt circuit instead of in circuit closing position, as shown.
- If adjustability of the thermal element is desired such adjustment may be accomplished in various ways, as by adjustment 15 of the post 21 rotarily, said post being mounted for such adjustment and being provided with means 23 to indicate the adjustment thereof.
- 20 What I claim as new and desire to secure by Letters Patent is:
1. The combination with a switch comprising a counter-balanced movable element containing a conductive fluid, said element 25 having means for lifting a relatively small amount of such fluid from the remainder thereof for circuit breaking, of thermo-responsive means for so operating said switch while maintaining the center of gravity of 30 said movable element and the contained conductive fluid substantially undisplaced vertically.
  2. The combination with a switch com-
- prising a movable element containing a conductive fluid, said element having means 35 for lifting a relatively small amount of such fluid from the remainder thereof for circuit breaking, a knife-edge pivoted counterbalanced oscillatable support for said movable element providing for movement 40 of said element to control circuit while maintaining the collective center of gravity of said element and said support substantially undisplaced vertically, of thermo-responsive means for so actuating said support. 45
- 3: The combination with a switch comprising a movable element containing a conductive fluid, said element having means for separating a relatively small amount of 50 such fluid from the remainder thereof for circuit breaking, a knife-edge pivoted counterbalanced support for said element providing for movement thereof to control circuit while maintaining the collective center of gravity of said element and said support substantially undisplaced vertically, 55 of adjustable thermo-responsive means connected with said support for actuating the same, and means for varying the range of movement of said support under given thermal conditions. 60

In witness whereof, I have hereunto subscribed my name.

HENRY N. WADE.
